CLOSURE ARRANGEMENT FOR OPENING OF
SHEET-METAL CONTAINERS

Max Wells Williams, Waldershare Park, Dover,
England, assignor to American Flange & Manufacturing Co., Inc., New York, N. Y., a corporation of Illinois

Application November 4, 1939, Serial No. 302,874
In Great Britain October 28, 1938

10 Claims. (Cl. 29—148.2)

This invention relates generally to metallic containers such as drums, barrels and the like and has to do particularly with closure means for the openings therein and with methods or processes for forming and assembling such closure means. The types of containers normally employed for the transportation or storage of oil, gasoline, chemicals and the like readily lend themselves to being equipped with the closure means of this invention and to the performance thereon of the methods of the invention.

A principal object of the invention is to provide facilities for the proper reception of a closure plug in and a cap seal over a threaded closure part, or neck, surrounding an opening in containers of the types above described, such closure part, or neck, being formed directly out of the stock of the container wall around the opening.

Another principal object is to provide a method for forming closure parts of the foregoing character in a simple, economical manner.

Another object of the invention is to provide such closure part, or neck, with a reinforcement which, while reinforcing, also aids in retaining the threaded contour and cooperates with the threaded neck to provide a seal cap receiving portion.

Another object of the invention is the provision of a method for forming and assembling a closure part of the foregoing character by bending the metal of the container wall neck to form threads therein and also to form the mouth of said neck into gasket and seal cap receiving portions.

Still another object of the invention is the provision of a method for forming the above type of closure part by working the metal of the neck into a threaded formation having substantially the characteristics of standard pipe threads without materially weakening the metal so worked.

Other objects of the invention will in part be obvious and in part appear from the following description taken in conjunction with the accompanying drawings.

Heretofore the closure bushings, or flanges, used around the openings of containers of the character with which this invention is concerned have been generally of two types. One type was designed to be welded in place around the opening, while the other was designed to be pressed, or mechanically inserted, in the container wall about the opening therein. The welded type, whose popularity has waned considerably since

the advent of the pressed type, made necessary the use of a heavy piece of metal to overlie the container wall in order to assure that a proper and substantial weld could be formed. The weight of this member, however, was not its only drawback, for the quantity of metal going into it made it expensive as did the handling of it due to its weight. Furthermore, the weld was normally formed on the outside of the drum wall. It was unsightly, had to be done by hand by skilled workmen and, even at its best, might have to be repaired from time to time as leaks would set in due to corrosion at points where the container wall stock had warped at or near the weld under the original welding heat.

15 The pressed-in type of bushing, or flange, though having the advantages over the welded type of economy of construction and insertion, pleasing appearance, and sufficient rigidity without excessive weight, still requires that there be a joint between the container wall and the bushing or flange. The pressed-in constructions, however, have lent themselves more readily to improvement in closure plugs and in the manner in which such closure plugs are received therein. They have also lent themselves better to the securing of a cap seal over the closure.

20 It is not feasible to cut threads into a neck formed directly out of the container wall stock around the opening therein, as practically no material would remain in back of such threads, leaving the neck too weak to be reliable. Since ordinary plumbing fittings are secured in these openings, the threads provided around the same 25 need to be standard pipe threads. The problem of rolling or pressing the stock of the neck into such threaded formation has been a considerable one. An isolated solution of it has been attempted, but in that instance the resultant closure slips back in some respects into the welded field, since no provision is made for the more advanced type of closure plug nor for receiving any cap seal over the closure. No effective and complete solution of the problem then has been 30 forthcoming until applicant's present contribution.

35 In the solution provided by applicant every requisite of an effective closure is satisfied. In the first place, the methods disclosed provide for either rolling or pressing the container wall neck into the desired threaded formation. These methods are capable of being carried out by little additional equipment beyond that found in the ordinary machine shop and accordingly keep 40 the investment down to a minimum. Labor cost 45

is also minimized since the methods contemplate the complete transformation of the neck into its final form in one complete operation. As to the threaded neck, the same is satisfactory and durable standing alone, but also lends itself to reinforcement should the container on which it is formed be one intended for frequent use over a long period of years. In either instance, however, provision is made for effective reception of a closure plug and for sealing the opening when closed in a leak-proof and tamper-proof manner. Thus, the invention presents a marked advance in the art and a considerable step forward in the art of drum closing. For illustration, reference is made in the accompanying drawings in which—

Fig. 1 is an elevation, partly in section, of a piece of container wall stock showing a plain, unthreaded neck drawn about an opening therein;

Fig. 2 is a vertical section in the initial stage, including the neck to be worked on, of the mechanism illustrating the pressing method for forming the threads;

Fig. 3 is a similar section in the final stage;

Fig. 4 is a partial plan view and Figs. 5 and 6 are vertical sections in initial and final stages respectively of a type of mechanism which may be employed for forming the closure of the invention by rolling, the neck to be worked on being included;

Fig. 7 is an elevation, partly in section, showing the completed container wall neck ready to receive a closure plug and cap seal, such neck not being reinforced;

Fig. 8 is a similar view showing a neck reinforced with a ring;

Fig. 9 is another similar view wherein a different type reinforcing ring is employed and showing the manner in which the closure plug and seal cap are applied; and

Fig. 10 is a view similar to Fig. 9 showing a different type of reinforcing neck and cap seal receiving projection.

The showing in Fig. 1 is of an illustrative section of container wall stock 10 apertured at 11 and provided with a neck 12 drawn up out of the container wall stock to define the aperture 11. In this state, the neck is ready for pressing or rolling into a thread form and for the formation of a bead at the end of such threads. The method of pressing threads into the neck and beading over the end of the same is illustrated in the initial stage in Fig. 2 and in the final stage in Fig. 3.

In the Fig. 2 arrangement, the flat portion of the container stock 10 is shown as resting on the upper surface of the bed plate or other rigid support 13 of a press possessed of the required characteristics. A depression 14 centrally apertured at 15 extends downwardly from the upper surface of the plate 13. On the lower surface of the depression 14, an expanding mandrel, generally shown at 16, is mounted. This mandrel is made up of separated segments 17 of any desired number, four being shown, for the purposes of illustration. Considering the expanded mandrel 16 as a whole, the peripheral surface of its upper portion is shown to be provided with a threaded contour 18. The peak and root of this thread are shown as sufficiently blunt to avoid cutting the drum stock neck, but yet not blunt enough to preclude the formation of threads simulating standard pipe thread.

Below its threaded periphery 18, the mandrel 16 is inset to form a downwardly extending neck

19, the upper end of which neck is grooved at 20 to receive and locate a contracting spring 21. This spring extends completely around the mandrel and is located in tension thereon. Opposed 5 conical apertures 22 and 23 extend downwardly from the top and upwardly from the bottom of the mandrel 16, are centered on the center line thereof and are of corresponding slope. Complementary conical expanders 24 and 25 extend 10 downwardly into the upper cone 22 and upwardly into the lower cone 23 respectively, the arrangement being such that the upward travel of the expander 25 and the downward travel of the expander 24 are related to provide exactly equal 15 horizontal expansion of the segments 17 throughout the height of the mandrel 16 without any vertical displacement of the mandrel.

The neck 12, as shown in Figs. 2, 3 and 8, is surrounded by a continuous reinforcing ring 26 which closely overlies the neck and rests at its 20 bottom on the upper surface of the container wall stock 10. This ring, besides performing the eventual function of a reinforcement, initially acts as the female member into which the stock of the neck 12 is forced by the segments 17 of the mandrel 16 in the formation of threads in the neck 12. Accordingly, the ring 26 is internally threaded at 27 with threads which are complementary to the threads 18 of the mandrel 16. 25 The proper registry of the threads 18 and 27 can be readily obtained by the proper positioning of locating marks on the ring 26 and the mandrel 16. As can be readily seen, this registry is maintained throughout the expanding action of the 30 segments 17, since the same have merely a horizontal movement. Another factor to be considered is the diminishing thread impression which will occur between the segments should they be too few in number. This can readily be corrected 35 by a slight turning of the container wall 10 until a second locating mark on the ring 26 lines up with the locating mark on the mandrel 17. A shim 13', of thickness equal to the vertical travel of the helix of thread 27 resulting from the turning 40 of the wall 10, is slipped between the upper surface of member 13 and container wall 10 and a second expansion of the segments 17 is made.

The conical expander 24 is carried by a die plate 28 which is in turn rigidly secured to the 45 ram of the press or similar part of whatever machine is employed. Besides acting as such carrying member, the die plate 28 is also formed with a rolling surface 29 in its undersurface. This surface is formed in a circle complementary 50 to the circle of the neck 12 and has a sloping pickup portion 30 as well as a curved rolling portion 31. The surface is sequentially arranged with respect to the position of the expanding cone 24, so that the sloping portion 30 engages the upper end of the neck 12 at close to the 55 fully expanding position of the segment 17, while the slope 30 and the curve 31 have a fast action which enables them to curl the upper end of the neck 12 over the upper end of the ring 26 to form a bead 32 as shown in Figs. 3 and 8. 60 Besides acting to bead over the upper end of the neck 12, the surfaces 30 and 31 exert a compressive force on that neck to prevent a stretching action of the neck 12 and in effect to make sure that the stock of the neck 12 floods fully into the coming threads 18 and 27 to assure that a complete, even and smooth thread is provided. Should a second expansion be required and the 65 shim 13' used, the rolling surface 29 will merely serve to tighten the bead 32. Alternatively the 70

75

shim could be used in the initial position, the turning being reversed and the shim accordingly removed.

To summarize the method performed by the above described arrangement, a container wall, which has been perforated at 11 and which has a neck 12 drawn up around that perforation, has a reinforced internally threaded ring 26 slipped thereover, care being taken to assure that it is fitted down onto the upper surface of the wall 10. The neck 12 is then placed over the expanding mandrel 16, which is in contracted position due to the action of the spring 21, a check is made to see that the mandrel 16 and the ring 26 are properly registered and the cone 24 is engaged with the surface 22, following which it is forced downwardly at the same time that the cone 26 is being forced upwardly. Should sufficient spacing occur between the segments that a fade-out of the threads takes place therebetween, members 24 and 25 having been retracted, segments 17 being contracted by the spring 21, a slight turning of the wall 10 and an insertion of the shim 13 is made. The segments 17 are then again expanded to complete the thread.

In Figs. 4, 5 and 6, there is illustrated a method by which the stock of the neck 12 is bent into a threaded formation by a rolling rather than a pressing action. In this form, the outer, or female member, may be made of separable segments 34 and 35, as best shown in Fig. 4, these segments carrying the female thread 36 on their inner faces. Segments 34 and 35 could, however, merely be employed as backing members for a ring such as that shown at 26 and in fact could be incorporated in the scheme of Figs. 2 and 3, if so desired. However, the use of segments 34 and 35 in removable fashion enables a threaded neck to be formed without the inclusion of a ring such as shown at 26 and with a consequent saving.

In Figs. 5 and 6, the segments 34 and 35 are shown in section as brought into position over the neck 12 to be threaded. Internally of the neck 12 there is introduced a tapered rolling member 37, the entrant end of whose outer surface is substantially a flat cone 38. This cone expands into fully formed threads at 39 whose blunt peak and root will be effective when the member 37 is turned to roll the stock of the neck 12 against the threads 36 of the outer female members to form a thread 40 closely simulating a standard pipe thread without any cutting of the metal. This thread formation is shown best in Fig. 6. Suitable arrangements are made to assure that on the commencement of the action of the threads 39, the same will be in proper registry with the threads 36 in order that no jamming of the operation will take place.

The member 37 is formed centrally of its top with an octagonal nut-like portion 41 which is received in a comating depression in the lower face of the die plate 42. Any suitable means, such as the bolt here shown, may be employed to secure members 37 and 42 together. On the lower face of the member 42 where the same is met by the upper end of the threads 39, there is formed a circular rolling groove or surface 43. Since this surface closely follows the upper end of the threads 39, it is obvious that it will engage the neck 12 and turn the same over into a bead 44, while the member 37 is coming to the end of its threading action.

From the structure illustrating this method, it is seen that the container wall stock 10 is first formed with a neck 12, which neck is surrounded

5 by segments 34 and 35, the same being brought together to complete a circle. The next step is the introduction of the member 37 which first operates to open the mouth of the neck 12 and then, by gradually increasing thread contours, rolls the neck into a helical formation. By the time this rolling has been substantially completed the upper end of the neck 12 will have engaged with the surface 43, have been bent outwardly and turned over to form the bead 44. At this point, the segments 34 and 35 may be removed and the member 37 retracted. Obviously modifications in the structure shown to illustrate this method of threading container wall necks as well as modifications in the illustrative structure of Figs. 2 and 3 may be made without departing from the spirit and scope of the invention.

20 In Fig. 7, a container wall neck 12 is shown as formed with threads 40 at whose top there has been provided a gasket seat 45 and an outwardly turned cap seal receiving bead 44. This is the closure plug receiving neck which results from the method of Figs. 5 and 6, the showing here being of that form of the construction which is devoid of any reinforcing collar. It is to be noted in passing that, though the peak and root of the threads are not as sharp as would be the case were the threads cut, the threads have sufficient 25 of a V-shape to substantially simulate standard pipe thread and they in fact approach such thread to such an extent that they readily receive standard pipe fittings. Though the method of Figs. 5 and 6 has been referred to as the one employed in forming this type of neck, it is obvious that, by providing a removable ring in place of ring 21 of the system of Figs. 2 and 3, this neck could also be made in that manner.

30 In Fig. 8, a neck 12 is shown as threaded at 33, as provided with a plug gasket engaging surface at 46 and as beaded over at 32 to overlie the upper end of the reinforcing ring 26. This ring 26, besides strengthening the neck generally, acts as a backing and reinforcement for the actual 35 threads 33, since the ring itself is internally threaded at 27 and thus forms the female member during the formation of the thread 33.

35 With regard to the manner in which the closure plug and cap seal would be secured in place in the necks of Figs. 7 and 8, the same would closely approximate the showing in U. S. Patent No. 1,982,145 issued to John W. Shera on November 27, 1934. In using such cap seal on the Fig. 7 construction, it might be necessary to shorten the skirt of the same, and merely have such skirt crimped beneath the bead 44, as it would not be advisable to operate the sealing tool against the threaded neck 12.

40 In Fig. 9, there is shown a slightly modified form of construction, in which the closure plug and the cap seal are included. In this form the container wall neck 12 is shown as provided with rolled or pressed threads at 47 and as flared outwardly at 48 directly from the upper end of the threaded portion. In this instance, as distinguished from the construction of Figs. 7 and 8, the cap seal securing bead is not formed directly out of the container wall stock. A reinforcing ring 49, threaded at 50 to act as the female member during the formation of the threads 47, remains around the neck 12 to reinforce the same after completion of the threading. This ring 49 is cut away at 51 at the top of its threaded portion in such a manner as to provide a seat 45 for the reception of the outwardly bent portion

48 of the neck 12. The cut 51 is just deep enough to seat the portion 48 with its upper surface lying flush with the upper surface 52 of the ring 49 forming therewith a smooth gasket engaging surface. Around the periphery of the ring 49 at the top thereof, there is provided an outwardly extending semi-circular bead 53 whose upper surface merges with the surface 52.

A screw plug 54 having a head 55 and being grooved beneath that head at 56 to carry a gasket 57 is shown as secured in the neck. Obviously the gasket 57 will engage the flared gasket receiving seat formed at the mouth of the opening by the outward bending of portion 48 on the neck 12 and will be prevented from destruction by the timely engagement of the edge 58 of the plug head with the upper end of that gasket seat. The plug 54 having been secured in place, a cap seal 59 is secured thereover. This cap has a top portion 60 with a depressed gasket receiving surface 61 therearound and a skirt portion 62 extending downwardly from the portion 61. A gasket 63 is shown as secured in place inside of the cap in the pocket formed by the portions 61 and 62. This gasket is preferably secured to the cap, but may be separate from it if desired. This seal cap is secured in place by means of a tool which draws the skirt of the cap over the bead 53 thereby compressing the gasket 63 against the surface 52. This action is fully described in U. S. Patent No. 1,887,435 issued to Fleck W. Sample on November 8, 1932, so needs no further explanation.

A further modification is shown in Fig. 10 in which the neck 12, shown threaded at 64, has its upper end extended straight upwardly above the threads at 65 and then laterally at 66. The threaded reinforcing ring 67 is similar to the rings previously described with the exception that it is shorter than the same, terminating at the end of the threaded portion and having a separate collar 68 lying on top thereof. This collar has a somewhat rounded outer periphery 69 and has a width equal to the lateral extent of portion 66. As this collar may be made by a stamping or coining operation and as ring 67 has nothing but a threading operation performed on it, some economy is presented over the form shown in Fig. 9 on whose ring several machining operations must be performed.

Reverting to the Fig. 10 construction, it is seen that the plug 54 and the cap seal 59 are generally similar to their counterparts shown in Fig. 9. The only differences reside in the provision of a larger plug gasket receiving groove 70 carrying a larger plug gasket 71 which is required by the shape of the seat against which it engages. With regard to the seal cap, its construction is the same as that of the cap in Fig. 9, but on being applied it is not drawn into exactly the same shape as the Fig. 9 cap due to the flatness of the composite bead formed by the periphery of portion 66 and the face 69. The cap gasket 63 is engaged against the flat upper surface presented by the portion 66.

From the foregoing, the manner in which this invention solves outstanding problems in this art is obvious. Not only does it incorporate the most advantageous features previously known, but it also positively precludes any leakage between the bushing and the container wall by forming the same directly out of the container wall itself. While several forms of method and product have been shown and described, other changes in operations and in details and ar-

rangements of parts may be made without departing from the spirit and scope of the invention as defined in the following claims.

I claim:

1. The method of converting an integral upstanding neck surrounding the opening in a metal container wall into a closure receiving member which comprises, bending the stock of said neck into a formation presenting substantially a standard pipe thread and simultaneously therewith rolling the free end of said neck outwardly to provide a gasket receiving surface.

2. The method of forming a closure receiving member on a metal container wall which comprises drawing the stock of said wall around an opening therein into an integral upstanding neck, bending the stock of said neck into a contour presenting substantially standard pipe threads and, simultaneously with said bending, rolling the free end of said neck outwardly to present a gasket engaging surface.

3. The method of converting an integral upstanding neck surrounding the opening in a metal container wall into a closure receiving member which comprises swaging the stock of said neck to form inwardly and outwardly extending substantially standard pipe threads and, simultaneously with said swaging, compressing said neck axially to prevent undue thinning thereof during said swaging operation.

4. The method of converting an integral upstanding neck surrounding the opening in a metal container wall into a closure receiving member which comprises swaging the stock of said neck to form inwardly and outwardly extending substantially standard pipe threads and, simultaneously with said swaging, compressing said neck axially to prevent undue thinning thereof during said swaging operation and curling the free end of said neck outwardly to provide a gasket seating surface around the open mouth of said neck.

5. The method of converting an integral upstanding neck surrounding the opening in a metal container wall into a closure receiving member which comprises bending the stock of said neck laterally to a contour presenting substantially standard pipe threads and simultaneously therewith curling the free end of said neck outwardly upon itself to form a cap seal receiving bead.

6. The method of forming a closure receiving member on a metal container wall which comprises drawing the stock of said wall around an opening therein into an integral upstanding neck, swaging the stock of said neck into a contour presenting substantially standard pipe threads and, simultaneously with said swaging, compressing said neck axially to prevent undue thinning thereof during said swaging operation.

7. The method of converting an integral upstanding neck surrounding the opening in a metal container wall into a closure receiving member which comprises surrounding said neck with an internally threaded female die member, introducing a co-mating male die member within said neck, swaging the stock of said neck into an internally and externally extending threaded contour by means of the co-action of said male and female die members and, simultaneously with said swaging, bending the free end of said neck outwardly to provide a gasket engaging surface.

8. The method of converting an integral upstanding neck surrounding the opening in a

metal container wall into a closure receiving member which comprises surrounding said neck with an internally threaded female die member, inserting a co-mating male die member within said neck expanding said male die member to force the stock of said neck into a threaded contour by a means of the co-action of said male and female die members, compressing said neck axially to prevent undue thinning of the same during the expanding and turning the free end 10 of said neck outwardly over the end of said female die member to retain the same in place around the said neck.

9. In container construction, a container wall having an opening therein, an upstanding integral neck formed out of said wall and surrounding said opening, internally and externally extending threads formed in said neck by bending 15

the stock thereof and a reinforcing annular bead formed at the free end of said neck said bead extending outwardly and then reversely inwardly to terminate closely adjacent the threaded part of said neck.

10. In container construction, a container wall having an opening therein surrounded by an upstanding integral neck, part of said neck intermediate the ends thereof being provided with swaged substantially standard pipe threads and a reinforcing bead formed out of the stock of the free end of said neck, said stock forming said bead being bent outwardly and back inwardly substantially upon itself to form an annular reinforcement for the end of said neck and to aid in maintaining the swaged contour of said neck against shocks tending to distort the same.

MAX WELLS WILLIAMS.
